UNITED STATES PATENT OFFICE.

WILLIAM H. CAMERON, OF PITTSBURGH, PENNSYLVANIA, ASSIGNOR TO RADIUM CHEMICAL COMPANY, OF PITTSBURGH, PENNSYLVANIA.

HOLDING OR SUPPORTING MEANS FOR RADIUM-APPLYING MEANS.

Application filed February 21, 1922. Serial No. 538,172.

To all whom it may concern:

Be it known that I, WILLIAM H. CAMERON, a citizen of the United States, and a resident of Pittsburgh, in the county of 5 Allegheny and State of Pennsylvania, have invented certain new and useful Improvements in Holding or Supporting Means for Radium-Applying Means; and I do hereby declare the following to be a full, clear, and 10 exact description of the invention, such as will enable others skilled in the art to which it appertains to make and use the same.

This invention relates to improvements in holding or supporting devices for radium 15 applying means, and more particularly to means for facilitating the application of radium in the mouth, to the tonsils or to the posterior nasal space or in the throat of a patient,—one object of the invention being 20 to provide holding or supporting means for the purpose stated, which may be readily adjusted to the head of the patient and which shall be adjustable in such manner as to hold the device which carries the radium, 25 in close, accurate and continued contact with diseased tonsils or other affected parts in the mouth or throat of a patient.

With this and other objects in view, the 30 invention consists in certain novel features of construction and combinations of parts as hereinafter set forth and pointed out in the claims.

In the accompanying drawings; Figure 1 is a view illustrating the application of my 35 improvements to a patient; Figure 2 is a view, partly in section, of the applicator to which the radium carrying device is to be attached; Figure 3 is a perspective view of the device to be disposed in front of the 40 mouth of the patient for adjustably supporting the applicator; Figure 4 is a view of the same device showing the upper member thereof swung aside to permit the insertion or removal of the applicator; Figure 5 is an enlarged transverse sectional view 45 through one end portion of the device shown in figures 3 and 4; Figures 6, 7, 8, 9, 10, 11 and 12 are views showing the construction of one form of radium carrying means; 50 Figure 13 is a perspective view showing the holding and supporting devices, and Figure 14 is a perspective view showing a radium screen and means whereby it may be connected with the applicator shown in Figures 55 1, 2 and 13.

My improved holding or supporting means are to be applied to the head of a patient by means of a head encircling strap 1 in such manner that the member with which the applicator is connected will be disposed 60 immediately in front of the mouth of the patient, as indicated in Figure 1.

The vertical members 2 of the supporting means which are to be located in proximity to the jaws of the patient, each comprises 65 two plates or members 3, 4,—the upper portion of each member 3 being made to form a buckle 5 for connection with the head-encircling strap 1 and provided near its lower portion with a fixed screw 6 which passes through an elongated slot 7 in the lower plate or member 4, whereby the latter may be adjusted vertically, and a thumb nut 8 on each screw 6 serves to clamp each lower member in any desired position of vertical 70 adjustment. Each lower vertical member 4 is provided with a clamping loop or sleeve 9 which receives an arm 10 and the latter may be secured in any desired position of adjustment relatively to the arm 4 by means of 75 a thumb nut 11 on a screw 12 the latter projecting from a portion of the clamping sleeve and passing through the member 4.

The arms 10 project forwardly from the 80 vertical, adjustable supporting members 4, and to their forward ends, other forwardly projecting arms 13 are hinged as indicated 85 at 14. The forward ends of the arms 13 have inwardly projecting members 15, each 90 of which is provided at its free end with a ball 16 for connecting with a holder 17 to be disposed directly in front of the mouth of a patient. The holder 17 may comprise two parallel plates 18 and 19 spaced apart 95 by blocks or enlargements 20, 21 integral with the respective end portions of the plate 18. These blocks are made with sockets (such as indicated at 22, Figure 5) to receive the balls 16 on the inwardly projecting portions 15 of the arms 13, and thus the holder 17 is adjustably supported between the arms 13 through the medium of ball-and-socket 100 connections. In order to secure the holder rigidly at any desired adjustment, set screws 105 23 entering the blocks 20 and 21 are caused to engage the balls 16 as clearly indicated in Figure 5. A plate 24 is secured to the block or enlargement 21 and is provided with a flange 25 which overlies the latter, but is spaced somewhat therefrom. Between the 110

2
flange 25 and the top of the block 21, one end portion of the upper plate 19 of the holder is hinged or pivotally connected, as indicated at 26, so that said upper plate may 5 be swung aside to permit the insertion or removal of the handle portion of applicator. In order that the plate 19 may be moved a considerable distance without conflict with the plate 24, it may be notched as at 27, and 10 said plate 19 may be notched as at 28 for the accommodation of a headed pin 29 projecting upwardly from the block or enlargement 20. In order to prevent escape of the ball 16 from its socket in the block 20 when 15 the plate 19 is swung aside, a small retaining screw 30 may be provided in the block 20, as shown in Figures 4 and 5. The plates 18 and 19 of the holder 17 are provided with a series of aligning perforations 18^a, 19^a and 20 when the handle portion 31 of an applicator 32 shall have been placed in the holder as shown in Figures 1 and 13, it may be pivotally held in any desired adjustment relatively to the ends of the holder by means of 25 a headed pin 33 which may pass through any of the aligning perforations in the plates 18 and 19 and through a perforation in the handle portion of the applicator. For the purpose of effecting longitudinal adjustment of the applicator, the handle portion of the latter may be provided with a plurality of perforations 34.

The forward end of the applicator is provided with a head 35 having a seat 36 in its 35 end and having external threads for the accommodation of an internally threaded sleeve 37, the latter having an internal seat 38, and between said seats, a ball 38^a at one end of a rod 39 is disposed. The forward 40 end of the rod 39 is threaded to enter a nut 40 movably mounted on a radium-carrying device. The ball-and-socket connection between the body of the applicator and the rod 39 will permit adjustment of said rod to so 45 adjust the radium-carrying means as to properly position the latter and cause it to be brought into contact with the diseased part, and when so adjusted, said rod 39 will be clamped in position by turning the body 50 of the applicator or the sleeve 37 to clamp the ball 38^a between the seats 36 and 38.

The radium carrying device may be made in the form of a plaque or capsule 41 (Figures 8 and 9) containing a mass having incorporated radium salt or compound, and 55 removably mounted in a holder 42, such as shown in Figures 6, 7 and 12. The holder 42 may be provided with a socketed enlargement 43 in which the nut 40 may be movably mounted to receive the threaded forward end of the rod 39, and thus the radium-carrying device shown in Figures 6, 7, 8, 9 and 12 may be adjustably connected with the applicator.

60 65 If desired, the radium-carrying device

may be a metal radium screen 44 to contain a radium tube 45 as shown in figure 14, or the radium in the screen may be contained in one or more radium needles, according to the quantity of radium which the physician may desire to use in a grain case. The screen 44 may be provided with ears 46, between which a nut 47 is mounted by means of a pivot pin 48 secured to said ears and passing through said nut. The nut will be applied to the threaded end of the rod 39 and when the screen shall have been properly adjusted, the turning of the rod 39 will cause its forward end to engage the pivot pin 48 and hold the screen in adjusted position.

In order that the radium-carrying device shall be applied with yielding pressure to the affected part, a flexible device 49 is connected at one end with the handle portion of the applicator and at the other end with the applicator holder 17. This flexible device may consist of rubber or a coiled spring.

With the use of my improvements, radium-carrying means may be accurately applied to affected parts in the mouth or throat, or to the tonsils of a patient and held accurately in such position without any effort of the patient, for any desired length of time, and the devices for attaching the holding means to the patient, provide ample adjustment of the various parts to accommodate the particular patient to be treated.

Having fully described my invention what I claim as new and desire to secure by Letters-Patent, is:—

1. Means for supporting a radium-carrying device in the treatment of mouth and throat affections, comprising a holder, adjustable means for supporting said holder in front of the mouth of a patient, means for attaching said supporting means to the head of a patient, an applicator having laterally adjustable connection with said holder, means for adjustably connecting a radium-carrying device with said applicator, and flexible means connected with said applicator for effecting yielding pressure of the radium-carrying device to the affected part.

2. Means for supporting a radium-carrying device in the treatment of mouth and throat affections, comprising a holder having spaced members provided with aligning perforations, means for supporting said holder in front of the mouth of a patient, means for attaching said supporting means to the head of a patient, an applicator passing between the members of said holder and having a plurality of perforations, a pivot pin passing through any pair of aligning perforations of the holder members and through any one of the perforations of the applicator, and means for adjustably connecting a radium-carrying device with the applicator.

3. Means for supporting a radium-carrying device in the treatment of mouth and throat affections, comprising a holder having spaced members, one hinged to the other and said members having aligning perforations, an applicator passing between the spaced members of said holder, a pin passing through said applicator and through perforations in the holder members, means for supporting said holder in front of the mouth of a patient, and means for adjustably connecting a radium-carrying device with the applicator.
4. Means for supporting a radium-carrying device in the treatment of mouth and throat affections, comprising a holder, adjustable means for supporting said holder in front of the mouth of a patient, an applicator adjustably connected with said holder, said applicator including an externally-threaded part having a seat on one end, a sleeve threaded on said part and having an internal seat at one end, a rod having a ball disposed between said seats, and means for connecting a radium-carrying device with said rod.
5. Means for supporting a radium-carrying device in the treatment of mouth and throat affections, comprising a holder, an applicator supported by said holder, means for adjustably connecting a radium-carrying device with said applicator, arms having ball-and-socket connections respectively with respective ends of said holder, means for securing said connections against move-
ment, arms hinged to said first-mentioned arms, a plate adjustably secured to each of said last-mentioned arms, other plates adjustably connected with said first-mentioned plates, and a head-encircling strap with which said plates are connected.
6. In the means for facilitating the application of radium in the treatment of mouth and throat affections, the combination with a holder, means for supporting said holder in front of the mouth of a patient, an applicator adjustably connected with said holder and including a rod adjustably connected with the body of said applicator, said rod having a threaded portion, a radium-carrying device, and a nut movably connected with said radium-carrying device and with the threaded portion of said rod.
7. Means for supporting a radium-carrying device in the treatment of mouth and throat affections, comprising a holder, means for pivotally supporting said holder in front of the mouth of a patient, means for connecting the radium-carrying device with the applicator, and flexible means connected with said applicator for effecting yielding pressure of the radium-carrying device to the affected part.

In testimony whereof, I have signed this specification in the presence of two subscribing witnesses.

WILLIAM H. CAMERON.
